AUTOMOTIVE SHOCK ABSORBER

James F. Hobbins, Philadelphia, and Howard P. McJunkin, Jr., Feasterville, Pa., assignors to Hurst Performance, Inc., Warminster, Pa.

Filed Aug. 29, 1973, Ser. No. 392,461

Term of patent 14 years

Int. Cl. D12—16

U.S. Cl. D12—159

Fig. 1.

Fig. 2.

Fig. 3.

Fig. 4.

FIG. 1 is a perspective view of an automotive shock absorber showing our new design;

FIG. 2 is a side elevational view thereof;

FIG. 3 is a top plan view thereof; and

FIG. 4 is a bottom plan view thereof.

The broken line showing of the upper and lower end mountings in FIGS. 1 and 2 is for illustrative purposes only.

We claim:

The ornamental design for an automotive shock absorber, as shown and described.
